Barry Jay Kesselman
ATTORNEY

IMAGING APPARATUS

This is a division of application Ser. No. 519,034, filed Jan. 6, 1966, and now U.S. Pat. No. 3,485,738 issued on Dec. 23, 1969.

This invention relates in general to imaging systems and, more specifically, to an improved electrophoretic imaging system.

There has been recently developed an electrophoretic imaging system capable of producing color images which utilizes electrically photosensitive particles. This process is described in detail and claimed in U.S. Pat. Nos. 3,384,565; 3,384,566 and 3,383,993 all issued on May 21, 1968. In such an imaging system, variously colored light-absorbing particles are suspended in a nonconductive liquid carrier. The suspension is placed between electrodes, subjected to a potential difference and exposed to an image. As these steps are completed, selected particle migration takes place in image configuration, providing a visible image at one or both of the electrodes. An essential component of the system is the suspended particles which must be electrically photosensitive and which apparently undergo a net change in charge polarity upon exposure to activating electromagnetic radiation, through interaction with one of the electrodes. In a monochromatic system, particles of a single color are used, producing a single colored image equivalent to conventional black-and-white photography. In a polychromatic system, the images are produced in natural color because mixtures of particles of two or more different colors which are each sensitive only to light of a specific wavelength or narrow range of wavelengths are used. Particles used in this system must have both intense and pure colors and be highly photosensitive.

Ordinarily, electrophoretic imaging systems include a transparent, conductive injecting electrode upon which the dispersion of photosensitive particles in an insulating liquid is coated. The image to be reproduced is projected on the suspension to the injecting electrode. During exposure, a potential, usually of from 300 to 2,000 volts is imposed on the suspension between the injecting electrode and a relatively insulating blocking electrode. This blocking electrode, ordinarily in the form of a roller or an endless belt, consists of a conductive core with an insulating surface. This blocking electrode is passed across the surface of the liquid suspension during exposure. Unwanted photosensitive particles migrate to the surface of the blocking electrode, leaving an image on the injecting electrode corresponding to the original.

It has often been found that images produced by the system broadly described above have uneven density and are blotchy or mottled in appearance. It is theorized that the unevenness in the image is caused by varying corona discharge or air ionization between the blocking electrode and the injecting electrode as the blocking electrode approaches the particle suspension. While the system described above is often capable of producing excellent images, at times, especially during periods of high relative humidity, the images produced are not of commercially acceptable quality. Thus, there is a continuing need for improvements in image quality under all ambient conditions.

It is, therefore, an object of this invention to provide an electrophoretic imaging system which is devoid of the above-noted disadvantages.

It is another object of this invention to provide a method of eliminating varying corona discharge or air ionization between electrodes in electrophoretic imaging systems.

It is another object of this invention to provide an electrophoretic imaging system capable of producing images of uniform density under varied humidity conditions.

The foregoing objects and others are accomplished in accordance with this invention by filling the air gap between the electrodes in an electrophoretic imaging system with an insulating liquid before the electrodes are brought into proximity in the image-forming area. The insulating liquid may comprise any material which is sufficiently insulating to prevent corona discharge between the electrodes and which is compatible with the insulating liquid in which the imaging particles are

suspended. Preferably, the liquid should have a resistivity of about 10^7 ohm/cm.² or greater. It is also preferred that the liquid have the same general composition as the carrier liquid which the photosensitive particles are suspended to ensure compatibility should some of this liquid be carried by the roller into the imaging area. Suitable insulating liquids include Sohio Odorless Solvent 3440 (a kerosene fraction available from Standard Oil of Ohio), Isopar G (a long chain-saturated aliphatic hydrocarbon available from Humble Oil Company of New Jersey), Freon (a fluorinated hydrocarbon available from E. I. Du Pont de Nemours and Company), Fluorocarbon FC-75 (a polyfluorinated mixture of compounds containing eight carbon atoms, available from Minnesota Mining and Manufacturing Co.), Silicon Fluid SF-96 (a dimethyl silicane fluid available from General Electric), mineral oil, decane, dodecane, N-tetradecane, molten paraffin, molten beeswax or other molten thermoplastic material. Any other suitable insulating liquid may be used where desired.

The advantages of this improved electrophoretic imaging system will become further apparent upon consideration of the following detailed disclosure of the invention; especially when taken in conjunction with the accompanying drawing which shows a side view of a simple exemplary for carrying out the process of this invention.

Referring now to the FIGURE, there is seen a transparent electrode generally designated 1 which, in this exemplary instance, is made up of a layer of optically transparent glass 2 overcoated with a thin optically transparent layer 3 of tin oxide, commercially available under the name NESA glass. This electrode shall hereafter be referred to as the "injecting electrode." Coated on the surface of injecting electrode 1 is a thin layer 4 of finely divided photosensitive particles disposed in an insulating liquid carrier. The term "photosensitive" for the purpose of this invention, refers to the properties of a particle which, one attracted to the injecting electrode, will migrate away from it under the influence of an applied electric field when it is exposed to actinic electromagnetic radiation. For a detailed theoretical explanation of the apparent mechanism of operation of this imaging process, see the above mentioned U.S. Pats. Nos. 3,384,565; 3,384,566 and 3,383,993, the disclosures of which are incorporated herein by reference. Adjacent to the liquid suspension 4 is a second electrode 5 hereinafter called the "blocking electrode," which is connected to one side of the potential source 6 through a switch 7. The opposite side of potential source 6 is connected to the injecting electrode 1 so that when switch 7 is closed, an electric field is applied across the liquid suspension 4 between electrodes 1 and 5 as blocking electrode 5 passes over liquid suspension 4. An image projection made up of light source 8, a transparency 9, and a lens 10 is provided to expose the dispersion 4 to a light image of the original transparency 9 to be reproduced. Electrode 5 is made in the form of a roller having a conductive central core 11 connected to the potential source 6. The core is covered with a layer of a blocking electrode material 12, which may be Baryta paper or other suitable insulating material. The blocking electrode may, of course, be in any other configuration capable of contacting the suspension without relative movement at the suspension surface. Typical alternative configurations are described in copending application Ser. No. 452,651, filed May 3, 1965. The particle suspension is exposed to the image to be reproduced while potential is applied across the blocking and injecting electrodes by closing switch 7. Roller 5 is caused to roll across the top surface of injecting electrode 1 with switch 7 closed during the period of image exposure. This light exposure causes exposed particles originally attracted to electrode 1 to migrate through the liquid and adhere to the surface of the blocking electrode 5, leaving behind a pigment image on the injecting electrode surface which is a duplicate of the original transparency 9. After exposure, the relatively volatile carrier liquid evaporates off, leaving behind the image. This process, utilizing only components exemplified by those discussed above, is in itself, capable of ordinarily producing

good images. However, under certain circumstances, such as high humidity the image produced tends to have variable density and a mottled or blotchy appearance. It has been found that this problem may be overcome by providing an applicator means 13 to apply an insulating liquid to the surface of the blocking electrode 5 forming a pool at 14 which fills the gap between blocking electrode 5 and injecting electrode 1 until blocking electrode 5 reaches dispersion. The gap-filling insulating liquid may be applied by any convenient method. For example, the liquid may be applied by spray or dropper to the blocking electrode surface or to the injecting electrode surface at a location so as to fill the space between the electrodes. Where the particle suspension is, alternatively, coated onto the roller-blocking electrode instead of the injecting electrode, the corona-preventing liquid may be applied to the injecting electrode, either by moistening the entire surface of the injecting electrode or by forming a pool at the gap between the electrodes. It appears that this gap-filling insulating liquid prevents corona discharge or air ionization between electrodes 5 and 1 and thus eliminates disruption of the image.

Any suitable insulating liquid may be used as the carrier for the photosensitive particles in this system. Typical carrier materials are decane, dodecane, N-tetradecane, paraffin, beeswax or other thermoplastic materials, Sohio Odorless Solvent 3440, (a kerosene fraction available from Standard Oil Company of Ohio) and Isopar-G (a long chain saturated aliphatic hydrocarbon available from Humble Oil Company of New Jersey).

As discussed above, any suitable insulating liquid may be used to fill the gap between the injecting and blocking electrodes. Good quality images have been produced with voltages ranging from 300 to 5,000 volts, in the apparatus of the FIGURE.

The following examples further specifically define the present invention with respect to the use of an insulating liquid between the electrodes before imaging in an electrophoretic imaging system. Parts and percentages are by weight unless otherwise indicated. The examples below are intended to illustrate various preferred embodiments of the present invention.

All of the following examples are carried out in an apparatus of the general type illustrated in the FIGURE with the particle mix 4 coated on a NESA glass substrate through which exposure is made. The NESA glass is connected in series with a switch, a potential source, and the conductive center of a roller having a coating of Baryta paper on its surface. The roller is approximately 2½ inches in diameter and is moved across the plate surface at about 1.45 centimeters per second. The plate employed is roughly 3 inches square and is exposed to a light intensity of about 8,000 foot candles as measured on the uncoated NESA glass surface. The suspension is exposed to an image by means of a conventional transparency. Examples I—V use a black-and-white transparency and produce monochromatic images. Examples VI—X use a "Kodachrome" transparency and produce full color images. All pigments which have a relatively large particle size as received commercially or as made are ground in a ball mill for 48 hours to reduce their size to provide a more stable dispersion which improves the resolution of the final images.

EXAMPLE I

About 8 parts of 2, 4, 6-tris(3'-pyrenylazo) phloroglucinol is mixed with about 100 parts Sohio Odorless Solvent 3440. This dispersion is coated onto the NESA glass substrate. No liquid is introduced into the gap between the roller electrode and the NESA glass substrate; leaving a small air gap therebetween. Relative humidity is measured and is found to be about 35 percent. A potential of about 2500 volts is imposed on the roller electrode during exposure. After exposure, an image corresponding to the original is seen on the NESA surface and a negative image is seen on the Baryta surface of the roller electrode. The positive image is of excellent quality but with slight variations in density across the image surface.

EXAMPLE II

The imaging process of Example I is repeated, except that sufficient Sohio Odorless Solvent 3440 is applied to the roller electrode before imaging to fill the air gap between the roller electrode and the NESA glass substrate before the potential is applied between the electrodes. After exposure, an excellent image corresponding to the original is observed on the NESA surface. Resolution and contrast are equal to that produced in Example I and image density is somewhat more uniform across the image surface.

EXAMPLE III

The imaging process of Example I is repeated, however, the relative humidity is maintained at about 85 percent. An image of good quality but with severe variations in density and a mottled and blotchy appearance results.

EXAMPLE IV

The imaging process of Example III is repeated, except that sufficient Sohio Odorless Solvent 3440 is applied to the surface so as to fill the air gap between the roller electrode and the NESA surface before potential is applied across said electrodes. The image produced is of excellent quality with much improved image density uniformity.

EXAMPLE V

The imaging process of Example IV is repeated, except Isopar-G is applied to the blocking electrode surface instead of the Sohio Odorless Solvent 3440. The image produced is of excellent quality with very uniform density across the image surface.

EXAMPLE VI

A pigment mix is prepared comprising equal parts of a yellow pigment, Albol Yellow GC, 1, 2, 5, 6-di(C, C'-diphenyl)-40 pyrazol-anthraquinone, C.I. No. 67300, available from General Dyestuffs; a magneta pigment, Locarno Red X-1686, 1-(4'-methyl-5'-phyloroazobenzene-2'-sulfonic acid)-2-hydroxy-3-naphthoic acid, C.I. No. 15865, available from American Cyanamid; cyan pigment, a cyan pigment, Monolite Fast Blue GS, a mixture of alpha and beta forms of metal-free phthalocyanine, available from Arnold Hoffman Company. About 8 parts of this mixture is dispersed in about 100 parts Isopar-G and the suspension is coated onto the NESA glass substrate. No liquid is applied to the roller electrode surface, leaving an air gap between the roller electrode and the NESA glass substrate. Ambient relative humidity is about 40 percent. A potential of about 2500 volts is imposed on the roller electrode during exposure. After exposure, a full color image corresponding to the original is seen on the NESA surface. This image is of excellent quality, however, there is a noticeable variation in image density across the image surface.

EXAMPLE VII

The imaging process of Example VI is repeated, except that sufficient Sohio Odorless Solvent 3440 is applied to the roller electrode surface so as to fill the gap between the roller electrode and the NESA glass substrate before potential is applied across the electrodes. Again, the image produced is of excellent quality. Here, however, image density is uniform across the image surface.

EXAMPLE VIII

The imaging process of Example VI is repeated, except that ambient relative humidity is maintained at about 85 percent. The image produced is of satisfactory quality, but with severe variations in image density across the image surface, giving a blotchy or mottled appearance to the image.

EXAMPLE IX

The imaging process of Example VIII is repeated, except that sufficient Sohio Odorless Solvent 3440 is applied to the roller electrode surface so as to fill the air gap between the roller electrode and the NESA glass substrate before a potential is applied across the electrodes. The image produced is of excellent quality with very little variation in image density across the image surface.

EXAMPLE X

10

The imaging process of example IX is repeated, except that the liquid applied to the roller electrode surface to fill the air gap is decane, instead of Sohio Odorless Solvent 3440. Again, an excellent image is produced with little variation of density 15 across the image surface.

Although specific components and proportions have been described in the above examples, relating to electrophoretic imaging, other suitable materials, as listed above, may be used with similar results. In addition, other materials may be added to the gap filling insulating liquid or to the particle suspension to synergize, enhance, or otherwise modify their properties. For example, the particle dispersions may be dye sensitized or electrically sensitized, if desired, or may be mixed or otherwise combined with other photosensitive materials, both organic and inorganic.

Other modifications and ramifications of the present invention will occur to those skilled in the art upon a reading of the present disclosure. These are intended to be included within the scope of this invention.

What I claim is:

1. An apparatus for electrophoretic imaging comprising:
  - a. at least two electrodes, at least one of which is a blocking electrode movable relative to said other electrode,
  - b. a suspension of photosensitive pigment in a liquid carrier on a first portion of said other electrode,
  - c. means to fill a gap between said blocking electrode and a second portion of said other electrode with an insulating liquid,
  - d. means to apply an electric field between said electrodes, 40 and
  - e. means to simultaneously project an image on said suspension and to move said blocking electrodes relative to said

45

- other electrode in contact with said suspension.
2. The apparatus of claim 1 wherein one of said electrodes is at least partially transparent.
3. An apparatus for electrophoretic imaging comprising in combination:
  - a. a first electrode having a suspension of a photosensitive pigment in a liquid carrier maintained on a first portion thereof,
  - b. a second electrode capable of being a blocking electrode maintained in near contact with a second portion of said first electrode thereby providing a gap therebetween,
  - c. means to present an insulating liquid in a gap between said second electrode and a second portion of said first electrode,
  - d. means to apply an electric field between said electrodes, and
  - e. means to simultaneously project an image on said suspension and to move said second electrode relative to said first electrode in contact with said suspension.
4. The apparatus of claim 1 further including means to move said electrodes relative to each other such that said second electrode contacts the suspension on said first portion of said first electrode while maintaining the insulating liquid therebetween.
5. Apparatus for electrophoretic imaging comprising in combination:
  - a first electrode capable of supporting a suspension of photosensitive pigment in a liquid carrier on a surface thereof,
  - a second electrode capable of being a blocking electrode maintained in at least near contact with said first electrode and being shaped for providing a nip between said electrodes,
  - means to present an insulating liquid at the entrance to the nip between said electrodes,
  - means to move said electrodes relative to each other whereby the surfaces of the electrodes are traversed by the nip formed therebetween,
  - means to simultaneously apply an electric field between said electrodes, and
  - means to project an image on said suspension during the traversing movement of said electrodes.
